(57) **CLAIM**

What is claimed is the ornamental design for an optical disc labeling device, as shown and described herein.

DESCRIPTION

FIG. 1 is a front plan view of an optical disc labeling device, in an opened condition showing our new design;

FIG. 2 is a back plan view thereof;

FIG. 3 is a perspective view thereof;

FIG. 4 is a bottom view thereof;

FIG. 5 is a top view thereof;

FIG. 6 is a right side view thereof; and,

FIG. 7 is a left side view thereof.

It is to be noted that certain design features of FIGS. 1-7 are shown in phantom or broken lines. Phantom or broken lines are provided to include disclosure about certain optional and illustrative design features; however, phantom or broken lines form no part of this claimed invention herein.
